UNITED STATES PATENT OFFICE.

JAMES G. CRAWFORD, OF BOSTON, MASSACHUSETTS.

WASHING-MACHINE.

SPECIFICATION forming part of Letters Patent No. 235,073, dated December 7, 1880.

Application filed July 26, 1880. (No model.)

To all whom it may concern:

Be it known that I, JAMES G. CRAWFORD, of Boston, in the county of Suffolk and State of Massachusetts, have invented a new and 5 Improved Washing-Machine, of which the following is a specification.

In this improvement the dasher is constructed with corrugated sides and has stationary vertical paddles or partitions, and the tub holding each dasher is provided with a bonnet adapted to prevent small garments, such as collars, &c., from dropping into the space between the tub and dasher. The corrugated sides of the dasher increase and give greater 10 variety to the motion of the water. The mechanism for operating the device is fully described 15 below.

In the accompanying drawings, in which similar letters of reference indicate like parts, 20 Figure 1 is an elevation of my improved machine carrying two tubs. Fig. 2 is a plan view with a portion of the bonnet removed from one tub and the second tub removed. Fig. 3 is an enlarged plan of a tub with a portion of the 25 bonnet removed. Fig. 4 is a vertical section of a tub.

a is the frame supporting the tubs b b, of which there may be any number. Within each tub b is a dasher, e, having corrugated sides c' and perforated bottom c'', and provided with vertical stationary radial paddles or partitions d upon its bottom. The dasher sits upon a carriage or round plate, e, provided with lugs e', which enter the bottom of the dasher, and the 35 carriage is fixed to a shaft, f, which passes down through the tub b and supports the dasher. This carriage e e' and shaft f were described by me in an application for a patent filed April 14, 1880.

Hot water, into which steam is often injected, is let into the tubs, which are stationary, and passes through the perforated bottom c'' into the dasher, filling it to a point below the top of its corrugated sides. The clothes are placed 45 in the dasher, and reciprocating rotary motion is applied to the shaft f (by mechanism below described) and thence to the dasher, which, by means of its paddles d and corrugated sides c', dashes the water about in a lively manner and 50 thoroughly cleanses them.

In order to prevent the smaller articles of clothing from entering the space between the dasher and tub, a bonnet, g, is placed upon the tub b, of the shape shown, and extends inwardly over the top of the dasher, covering 55 the space between it and the tub.

Motion is applied to the shaft f, connecting with each dasher, as follows: A driving-wheel, h, is driven by a belt, and has on each side a crank, k, fixed to the shaft h'. Connected with each crank is a rod, l, pivoted in a horizontal bar, m, sliding in supports m'. A rod, n, is pivoted to the bar m and the rod p, which latter is fixed to the shaft f. (See Fig. 2.) The driving-wheel h, through the crank k and connecting-rod l, imparts reciprocating motion to the bar m, which, by means of the rods n p, imparts reciprocating rotary motion to the shaft f and dasher e.

In the drawings mechanism exactly in duplicate extends to each tub—to the first tub on one side, and to the second on the opposite side, of the frame—from the driving-shaft h'. Both tubs could be connected with the same bar m, and as many tubs may be added 75 as desired.

This machine being intended mainly for use in large laundries, steam-power is usually applied.

Having thus fully described my invention, 80 what I claim, and desire to secure by Letters Patent, is—

1. The combination of the stationary tub b with the rotary reciprocating dasher e, provided with a corrugated wall and a perforated 85 bottom, substantially as and for the purpose described.

2. The combination of the tub b with the rotary reciprocating dasher e, having a corrugated inner wall, perforated bottom, and perforated cross-bars or partitions d, set at right angles to said bottom, substantially as and for 90 the purpose specified.

JAMES G. CRAWFORD.
